BED CHAIR

Leo Lombardi, Charles H. Spicer, and Christian F. Christensen, Los Angeles, Calif.

Application July 3, 1940, Serial No. 343,872

3 Claims. (Cl. 155—49)

This invention relates to furniture and more particularly to a bed chair, it being one object of the invention to provide an article of furniture which may be used as a chair or converted into a bed.

Another object of the invention is to provide an article which is normally used as a chair and has an upholstered back capable of being swung from an upright position, in which it serves as a back for the chair, to a reclining position in which it serves to cooperate with the seat of the chair to form a bed or couch.

Another object of the invention is to provide the tiltable back of the chair with improved means for holding the same in a raised position in which it serves as a back for the chair, the securing means being of such construction that the back may be angularly adjusted and secured at a desired incline or completely lowered to a reclining position to form part of a couch or bed.

Another object of the invention is to provide improved fastening means for the chair back which is urged toward a securing position so that there will be no danger of the back accidentally slipping and moving to a lowered position prematurely.

Another object of the invention is to provide the chair with a seat including companion upholstered sections cooperating with each other to form a seat for the chair and capable of being easily moved to an extended position in which they cooperate with the lowered back to form a bed or couch.

Another object of the invention is to provide an article of furniture which normally appears to be merely a large, comfortable chair but may be quickly and very easily converted into a bed or couch type.

The invention is illustrated in the accompanying drawings, wherein:

Fig. 1 is a side elevation of the improved bed chair.

Fig. 2 is a view showing the bed chair adjusted for use as a bed.

Fig. 3 is a top plan view of the bed chair adjusted for use as a bed.

Fig. 4 is a longitudinal sectional view on the line 4—4 of Fig. 3.

Fig. 5 is a sectional view taken vertically through the back of the chair on the line 5—5 of Fig. 7.

Fig. 6 is a view similar to Fig. 5, showing the latch moved to releasing position.

Fig. 7 is a view taken vertically on the line 1—7 of Fig. 5.

Fig. 8 is a sectional view taken horizontally through the back on the line 8—8 of Fig. 5.

Fig. 9 is a side elevation showing the chair shifted downwardly by the weight of a person sitting in the chair.

Fig. 10 is a sectional view on an enlarged scale taken vertically on the line 10—10 of Fig. 1.

Fig. 11 is a similar view on the line 11—11 of Fig. 9.

This improved chair bed has side members 1 constituting arms for the chair. The side members or arms are of hollow formation, as shown in Fig. 7, and have their rear portions reduced in width from their inner sides to provide shoulders 2 which extend vertically at a rearward incline from their lower ends toward their upper ends. A rectangular frame 3 is mounted between lower ends of the side members 1 and constitutes a support for the seat of the chair. Front and rear portions of the side members are provided with feet 4 and, in order to permit the chair bed to be easily moved from place to place, there have been provided castors 5 which rest on the floor at all times.

Each castor is mounted as shown in Figs. 10 and 11, and referring to these figures, it will be seen that the shank 6 of each castor is rotatably mounted through the bottom 7 of a cylindrical socket 8 and engaged in the bore 9 of a block 10. This block is slidable vertically in the socket 8 and engaged by a spring 12 which is fitted within the upper portion of the socket with its upper end bearing against a plug 13, which plug is screwed into the socket and serves to confine the spring in the socket and also serves to properly tension the spring so that the springs for the four castors serve to normally hold the chair in the raised position shown in Fig. 10, permitting it to be easily rolled along a floor. The weight of a person occupying the chair or bed, when the chair is converted into a bed, will depress the same and cause the feet 4 to rest upon the floor, as shown in Figs. 9 and 11, and exert frictional binding which will prevent the chair or bed from moving along the floor out of a desired position. Consequently, creeping of the chair or bed will be prevented.

The seat for the chair has a box-like frame or base 14 carrying a cushion 15. The base has side rails 16 which rest on the side bars of the frame 3 and, at its rear or inner end, carries depending blocks 17 which serve as stops to limit forward sliding movement of the seat by engage-

ment with the front cross bar of frame 3. This is clearly shown in Fig. 4. It should be noted that the side rails 16 of the base have sloping lower edge faces which rest against the side bars of the frame 3 and cause the seat to extend rearwardly at a downward incline when the seat is in its retracted position shown in Fig. 1. The front plate 17 extends downwardly below the side rails to serve as a floor-engaging support for the front end of the seat and also constitutes an abutment for engaging the front bar of frame 3 and limit rearward movement of the seat when in a retracted position. An upper cushion 18 normally rests on the lower cushion 15 and, at its rear end, is connected with the rear end of the lower cushion by a strip of fabric 19 to provide a hinged connection which holds the upper cushion connected with the lower cushion but allows it to be swung rearwardly to lowered position. When the upper cushion is swung rearwardly to lowered or reclining position, it rests on the frame 3 back of the cushion 15 and the base 14 carrying the same, as shown in Fig. 4. The two cushions then form sections of a bed or cot.

The back 19 of the chair has side bars or posts 20 which are pivotally connected with the side bars of frame 3 and the side members 1 of the chair, by hinges 21. These hinges fit between frame 3 and side members 1, where they are pivotally mounted by pivot rods or bolts 22 and, when the back is swung upwardly to raised position its forward movement is limited by the shoulders 2 of the side members 1 of the chair. A plate or panel 23, forming a backing for a cushion 24, is secured against the side posts and constitutes a firm reinforcement for the cushion. It should be noted that the lower or forward portion 24' of cushion 24 is of reduced width in order that it may fit between side members 1 when the back is in raised position and that when the back is in raised position, the wider portion of the cushion 24 may rest on the side members or arms 1 in advance of the shoulders 2. Guide plates 25 and 25a which are enclosed in a housing 26, are secured against outer side faces of the side posts, and the bottom of this housing is formed with openings 26a through which pass the side posts 20 and bars 27 which have contacting engagement with rear faces of the posts. These bars 27 extend longitudinally of the posts between the plates 25 and 25a and, at their lower ends, are connected with upper ends of bars 28 carrying at their lower ends hinges 30 through which pass hinge pins 31 carried by frame 3 and the side members 1. By this arrangement, the bracing bars 28 may have swinging movement and the bars 27 slide longitudinally as the back is swung to a raised position or to the lowered position shown in Fig. 4, wherein the cushion 24 of the back is flush with cushion 18 and, together with cushions 18 and 15, form a complete padded bottom or mattress for the bed. Rollers 25b are mounted between the lower guide plates to engage the bars 27 and cause the bars to be held firmly against the posts but slide easily.

When the back is in the raised position shown in Fig. 1, or shifted rearwardly somewhat to a more comfortable angle, it must be secured in set position and in order to do this there have been provided gripping blocks 32. These blocks are located back of bars 27 between the guide plates and are connected with the posts 20 by pairs of links 33. The links are located at opposite sides

of the bars 27 intermediate the upper end lower guide plates and are pivotally connected with the posts by pins 34. The other ends of the links are pivotally connected with the gripping blocks 32 by pins or rods 35 which protrude, as shown in Figs. 7 and 8, and are engaged with lower ends of springs 36. Upper ends of the springs are anchored to screw eyes 37 and tension of the springs serves to urge the gripping blocks upwardly to the position shown in Fig. 5, and cause the blocks 32 to have firm gripping engagement with the bars 27. Therefore, the bars 27 will be frictionally gripped between the posts and blocks and the back will be firmly held in upright position and prevented from moving out of a desired position of adjustment. Friction strips 32a are provided along confronting faces of the posts 20, bars 27 and blocks 32, to assist in creating tight frictional grip when the blocks are in gripping position. A rod or shaft 38 is rotatably mounted through the upper portion of the housing or casting 25 transversely of the back with one end protruding a sufficient distance to carry a handle or lever 39 by means of which the shaft is to be turned. It will be obvious that a lever handle may be mounted upon each end of the shaft, if so desired, and thus permit the shaft to be turned from either side of the chair.

Arms 40, which constitute cams, are fixedly carried by the shaft 38 over upper ends of the blocks or bars 32 and normally engage lower ends of the sloping upper end faces 41 of these gripping bars, as shown in Fig. 5. When the shaft is turned by means of its handles 39, the arms 40 will be swung rearwardly and their lower ends will act against the sloping upper ends of the blocks 32 to shift the blocks downwardly, and during their downward movement they will be shifted out of gripping engagement with the bars 27, due to the fact that the links will move from the inclined position of Fig. 5 to the position of Fig. 6, wherein they extend at right angles to the bars 27. The bars 27 can then slide freely along the posts and the back of the chair may be swung rearwardly to an angularly adjusted position, or lowered to the reclining position shown in Fig. 4. When the handle is released, the springs 36 will exert upward pull on the pins 35 and return the blocks 32 to a gripping position, in which position they cause the bars 27 to be again firmly gripped and the back of the chair held in adjusted position. It will thus be seen that the device may be very conveniently used either as a chair or as a bed and that when used as a chair, the back may be adjusted to any desired angle and securely held in the adjusted position. When upward pull is exerted upon the chair back to raise same, the blocks will be urged downwardly toward releasing position and the chair back may be swung upwardly without actuating the handle 39 to move the blocks to the releasing position.

Having thus described the invention, what is claimed is:

1. In a combination chair and bed, side members constituting chair arms, a seat between the side members, a back for the chair having side posts pivoted at their lower ends to mount the back for swinging movement from a raised position rearwardly to a lowered position for cooperating with the seat to form a bed, braces pivoted at their lower ends rearwardly of the back, bars pivoted at their lower ends to upper ends of the braces and extending upwardly therefrom in flat contacting engagement with rear faces of

the posts and being slidable longitudinally of the posts, clamping blocks mounted for shifting movement longitudinally of the posts and towards and away from the posts into and out of position for gripping engagement with rear faces of said bars to hold the bars stationary and retain the back in raised position at a desired incline, means for yieldably holding the blocks in position to grip the bars, and means for moving the blocks to releasing position allowing movement of the back to adjusted positions.

2. In a combined chair and bed, side members constituting chair arms, a seat between the side members, a back for the chair having side posts pivoted at their lower ends to mount the back for swinging movement from raised position rearwardly to a lowered reclining position for cooperating with the seat to form a bed, braces pivoted at their lower ends rearwardly of the back, bars pivoted at their lower ends to upper ends of the braces, said bars bearing against rear faces of the posts and being slidable longitudinally thereof, clamping blocks for engaging rear faces of said bars, links extending across said bars and pivoted to the posts and the blocks and mounting the blocks for movement into and out of position for gripping the bars, resilient means normally holding the blocks in gripping position, and releasing means including cams for engaging the blocks and moving the same to a position out of gripping engagement with the bars. 30

3. In a combined chair and bed, side members constituting chair arms, a seat between the side members, a back for the chair having side posts pivoted at their lower ends to mount the back for swinging movement from raised position rearwardly to a lowered reclining position for cooperating with the seat to form a bed, braces pivoted at their lower ends rearwardly of the back, bars pivoted at their lower ends to upper ends of the braces, said bars bearing against rear faces of the posts and being slidable longitudinally thereof, side walls extending rearwardly from the back, clamping blocks for gripping rear faces of said bars, links extending across the bars and pivoted to the posts and blocks to mount the blocks for movement into and out of gripping engagement with the bars, springs for urging the blocks upwardly and tilting the links to move the blocks to gripping position, a shaft rotatably mounted between the side walls, cams carried by said shaft, said blocks having sloping upper faces engaged by said cams, and means for turning the shaft in a direction to move the cams across the sloping faces of the blocks and exert pressure thereon to shift the blocks longitudinally and swing the links to move the blocks out of gripping engagement with the bars to permit tilting adjustment of the chair back.

LEO LOMBARDI.
